Primary Examiner — Ian Simmons*Assistant Examiner* — Shannon Morgan(74) *Attorney, Agent, or Firm* — Cantor Colburn LLP(57) **CLAIM**

We claim the ornamental design for a display screen or portion thereof with animated graphical user interface, as shown and described.

DESCRIPTION

FIG. 1 is the first image in a sequence for a display screen or portion thereof with animated graphical user interface showing our new design;

FIG. 2 is the second image thereof;

FIG. 3 is the third image thereof;

FIG. 4 is the fourth image thereof;

FIG. 5 is the fifth image thereof;

FIG. 6 is the sixth image thereof; and,

FIG. 7 is the seventh image thereof.

The appearance of the transitional image sequentially transitions between the images shown in FIGS. 1-7. The process or period in which one image transitions to another forms no part of the claimed design. The outer broken line perimeter shown in FIGS. 1-7 represents the display screen or portion thereof, and the inner broken lines shown in FIGS. 1-7 represent graphical user interface; the broken lines form no part of the claimed design.
